[57] CLAIM

The ornamental design for a toy whistle, as shown and
described.

DESCRIPTION

FIG. 1 is a top perspective view of a toy whistle showing
the new design;

FIG. 2 is a bottom perspective view thereof;

FIG. 3 is a right side elevational view thereof, the left
side elevational view being a mirror image thereof;

FIG. 4 is a front elevational view thereof; and,

FIG. 5 is a rear elevational view thereof.

*FIG. 1**FIG. 2**FIG. 3**FIG. 4**FIG. 5*
